SHIPPING CONTAINER

Charles C. Stetson, St. Paul, Minn.

Application May 8, 1933, Serial No. 669,901

6 Claims. (Cl. 105—366)

My invention relates to a shipping container which is sized to be of desirable proportions so that it will fit with a similar container, two abreast, inside of the ordinary box car, in a manner to nearly fill the width thereof and thus the containers may brace each other at the sides while positioned side by side as twin containers. The advantage of my containers in this particular size also permits the same to be loaded into the box car so that when they are in place, side by side in the ordinary box car of approximately forty feet long, two pairs of these containers can be positioned in each end of the box car, while another single container may be set in or about the middle of the car with other merchandise or goods loaded about the same, thereby filling the box car in a desirable manner. With the containers set in this position there is little surface exposed to a thief or anyone who might tamper with the containers. This is a material advantage as it protects the shipper using a container of this character.

A feature of my container resides in equipping it with strong skids for supporting the body of the container elevated sufficiently so that a warehouse lift-truck may be slid under the same between the skids and used to raise the container, so that the skids thereof are then free of the floor and permit the truck to be readily moved with the container as desired.

It is a feature to provide the bottom surface of the skids with a friction shoe which may be secured thereto in any suitable manner. This shoe may be made of any material which will increase the friction sufficient to prevent sliding of the containers on the floor which might more easily take place if the skids of the containers wear smooth after they have been used. The friction shoes may be attached in a manner so that they can be readily replaced after they become worn out. This friction means in the skids may also be in the form of resilient cushion elements, such as rubber or other similar means, which is supported within the skid. Several of these rubber cushions may be supported in each skid. The rubber cushions are removably supported within the skid, being held in a socket which fits into the body of the skid. The free end of the cushion which engages the surface of the floor is spaced from the body of the skid so as to permit slight movement of the container. This resiliently supports the container to permit it to shift slightly when carried in a railroad car, taking up some of the shock which might otherwise be transmitted to the container and its contents.

A feature of my shipping container resides in means for interconnecting the containers in tandem by a resilient member which serves as a bumper member and which is attached to each container on one end thereof. The other end

of each container has a yoke into which the bumper may engage. This permits the containers to be easily connected together when it is desired. The bumper member carried by each container also acts as a means of resiliently securing the container to the end of a railroad car, such as inside a box car. In this case the end of the car is provided with a suitable yoke into which the bumper may hook and thus the container is adapted to be held to the end of the car when it is desired. An advantage of this means of connecting my shipping container to the end of a box car or to a similar adjacent container, resides in forming the spring bumper and connector which is secured to the end wall of the box car or to the end of an adjacent container, in a manner so that as the shipping container is moved into the car and up against the end wall thereof, the mere lowering of the container by the lift truck causes the tongue of the bumper to hook into the yoke on the end of the box car wall by a sliding movement. The respective containers may be connected together in the same manner as just described.

A further advantage of the spring bumper and yoke connection either to the end wall of a box car or to the adjacent container, resides in the connecting of the containers in a manner so that the spring bumper serves a dual function. The bumper acts to pull or push as the direction of impact requires, to hold the container in place in the box car. It absorbs to a large degree the shock or strain against the end of the container in the coupling or uncoupling of box cars, or the starting of the train, and thus saves wear and tear on the container itself, as well as the contents thereof. The bumper is sufficiently strong to provide an adequate holding or connecting means and yet supplies the resiliency which is so much desired to avoid damage or shock to the contents.

Each of my shipping containers is made of metal walls having a duplex trussed cross section which reinforces the double metal sheets forming the walls and which are welded together in a manner to provide a smooth inner surface to the sides and top thereof, while the floor plates herefore described protect the bottom. The shipping containers are weather-proof, rat-proof, fire-proof, sanitary, and protect the contents against thieves.

My shipping containers are of a moderate size which permits them to be more easily handled without expensive equipment or hoisting means, owing to the fact that ordinary lift trucks may be slid under the same between the skids and then by a simple operation the containers are raised and may be trucked from place to place. The skids hold the body of the container up off of the floor away from dampness and thereby provide a better protection for the contents of the same.

50

55

60

The walls of the body of my shipping container are preferably made of duplex trussed steel plate which enables easy insulation with paper in the openings between the trussing ribs. When the walls are thus insulated, the contents are further protected against varying temperatures and weather conditions. The walls of the container may also be more fully insulated and protected by filling the spaces between the trussing ribs with a light-weight fibrous insulating material of any suitable nature, and this is a feature which is regarded as particularly advantageous in this form of construction. A further important advantage in the moderate size and easy manipulation of my container is that it can be readily placed on an automobile truck by the same hand operated lift truck which is used in positioning it in or removing the same from a railroad car. Thus the container with its cargo or load can be loaded at a point remote from the railroad station and not unloaded until at its destination where the goods in the same are to be delivered. This is not possible as far as I know with forms of shipping containers which have been used heretofore, most of which are of a heavier and more bulky type and not designed to be paired together or connected in series as I have set forth.

In the drawings forming a part of this specification:

30 Figure 1 illustrates a diagrammatic plan view of an ordinary railroad box car shown in cross section and showing my shipping containers arranged therein to illustrate the manner in which my containers can be set in pairs of twins in the box car, virtually filling the width thereof and also showing one of the shipping containers in line with the doors so that the same can be readily removed from the car.

Figure 2 is a perspective view of a pair of my shipping containers positioned adjacent each other to show the compact nature thereof and illustrating how they pair up in a railroad car.

Figure 3 is a plan view of my shipping container to show the rectangular formation thereof and approximating the overall dimensions thereof.

Figure 4 is an enlarged vertical cross section transversely through my shipping container, a portion of which is broken away.

50 Figure 5 is an enlarged detail section of one of the skids, showing the rubber cushion friction means in the skid.

Figure 6 is a perspective detail of a portion of one end of my shipping container.

55 Figure 7 is a perspective detail of the opposite end of the shipping container to that shown in Figure 6.

Figure 8 is a detail of the end inside wall of a railroad car, showing my connecting yoke secured thereto.

Figure 9 is a section on the line 9—9 of Figure 8.

Figure 10 is an enlarged section of the wall structure of my shipping container.

65 Figure 11 is a similar section to Figure 10, showing insulation between the sides and between the reinforcing truss portions.

Figure 12 is a plan detail of one end of my container, looking down on the spring bumper of the same.

70 My shipping container A is of a rectangular shape and is formed with a body portion, the walls of which are formed of smooth plates 10 and 11 of sheet steel, between which steel trusses 12 extend in a manner to space the plates 10 and 11

apart with the trussing zigzagging back and forth between the plates and having a contacting surface 13 to each of the plates 10 and 11 where the truss and the plates are welded together, making practically an integral structure for the walls of the container. This trussed wall construction provides a comparatively smooth outer and inner surface to the side walls 14 of the body of the container A.

The side walls 14 of the container rest and are connected to the bottom 15 with an overlapping connection as illustrated in Figure 4. The sides may be welded or secured to the bottom in any suitable manner. The top 17 is formed by two inclined portions which join to form an apex and are connected by the T-iron 18 longitudinally along the same, while the outer edges of the top slant toward the side walls 14 and are connected by the angle members 19 thereto. The end 20 of the container A is closed while the opposite end 21 is provided with a hinged door 22 which may be secured by the lock 23 as well as the catches and locks 24. The body of the container A is supported on longitudinally extending skids B. These skids extend along each side of the bottom of the container A and are shaped to taper down into a smaller shoe portion 25 which may be covered by a friction plate 26 made up of a material to resist free sliding of the skids B. The plate 26 may be replaceably secured to the skids B in any suitable manner so that they can be replaced when worn out. The skids B are formed with a recessed central portion 27 which permits the shipping container A to be easily moved over irregular surfaces without dragging of the skids even though the shipping container is not raised very high while moving.

The skids B are placed far enough apart so as to provide a space 28, illustrated in Figure 4, between the same so that a lift truck of a suitable character may be slid under the container A and be caused to lift the container sufficiently so that the truck can move the same from place to place.

Resilient cushions 30 which may be made of rubber or other suitable material can be placed in the skids B, and are held in the thimble 31 so that the cushions 30 may be removed and replaced when it is desired. These cushions have a floor engaging portion 32 which engages against the floor and causes the body of the cushion to be compressed by the weight of the container, however, the end 32 is small enough to provide a space 33 around the same which permits a slight shifting of the container A when it is subjected to jolting or jarring in a railroad car, owing to the movement of the train or switching of the same. This protects the contents of the container A by supporting the same in a resilient manner. The cushions 30 take the place of the friction shoes 26 and prevent the container A from sliding too freely.

Heretofore steel shipping containers have been objected to because the bottoms would wear smooth and they would slide too freely under jars or jolts, and this I have overcome by my friction plates 26 or the cushions 30. Further, I have provided a construction of container to more fully protect the contents of the same.

The sides 14 are provided with vertically extending spacers 34 which are placed in staggered relation so as not to align with an adjacent spacer 34 of another container A. These spacers hold the container apart so that they may be more easily moved by the lift trucks by twisting the same slightly in removing them from a railroad

car, or in tight places. The containers may be made with or without these spacer members 34.

The ridged top 17 gives more strength to the container, permits any moisture to readily drain off of the same, and prevents the container from being warped inwardly by placing ordinary loads on top of the same. For instance, when the containers A are used in the box car, like I have illustrated in Figure 1, long articles like rugs or other household goods, or other material, may be placed on top of the same, and with ordinary loads there need be no fear of injuring or bending the top of the container A.

I have shown by the dotted outline 35 in Figure 1, the approximate position of a lift truck D under one of the containers A. Nine containers A fit in a box car having an inner dimension of forty feet and six inches by eight feet and six inches, and the space around the center shipping container A can be filled with other material. When it is desired, the center container A can be removed and then the other containers A are easily accessible by shifting after removing the center container A. The diagram of Figure 1 is illustrative to more clearly define the practical nature of my shipping container A and to more fully illustrate the need of a container of about the proportions which I have illustrated and described and of the general construction of the same.

An advantage of my container is that it is comparatively light-weight owing to the trussed walls of the body of the same, and yet it is strong and durable, having several outstanding advantages herein pointed out. The end 21 of the container which supports the door 22 is provided with a yoke 37 secured centrally of the end 21. The opposite end 20 of the container A is adapted to support the spring member 38, the ends 39 of which are secured under the container A and adjacent the skids B. The resilient member 38 forms a cushion bumper extending along the container A more particularly for the reason that it is curved up and down between its ends, as illustrated in Figure 6, and back and forth horizontally to form the spring loops 38' adjacent the sides of the same and a center spring loop 40, each of which projects out from the end of the container A, as illustrated in Figure 13. At the center of the bumper or resilient member 38 I provide a downwardly depending tongue 41 which is adapted to fit into the opening 42 of the yoke 37 when the containers A are connected in tandem, as illustrated in Figure 1. The tongue 41 also is adapted to fit into the car yoke 42 which is secured to the end wall 43 of a railroad car in the manner illustrated in Figures 8 and 9. This yoke 42 has slanting bracket arms 44 which permit the container A to be slid against the yoke 42 so that the tongue 41 of the bumper and connector 38 will be slipped down into engagement with the yoke 42, when it is desired to connect the container A to the end wall of the car. The connecting of the container A to the end wall is a simple operation of the lift truck D. The container is run up against the yoke 42 while it is elevated on the lift truck D and then as the lift truck D lowers the container A, the tongue 41 slips into the yoke 42. The container A is removed in the same manner, by lifting the same out of connection with the yoke 42. This is simple and practical and performs an important feature in providing a container having a structure fulfilling the essential

requirements to make the same practical in use.

I have defined the several features of my shipping container including the reinforced side wall with the smooth inner surfaces for the entire container A, as well as smooth outer surfaces. 5 The trussed construction of the plates 10 and 11 for the entire body of the container A permits a lighter weight container to be used and yet a strong, durable body construction is provided. The features further include the connecting of 10 the containers in tandem and to the car, and providing end connector and bumper means, as well as yokes for interconnecting the containers.

It is also a material advantage to provide a resilient cushion in the skids which prevents 15 sliding of the containers A and also cushions the contents of the same. With these advantages my shipping container is more desirable than the heavy, bulky constructions of containers which have been used heretofore.

I claim:

1. A shipping container having, a body with a rectangular formation, the width of which will permit two of said containers to be positioned side by side in a railroad car of ordinary dimensions, 25 and substantially filling the width of the car, side walls on said body, spacers extending up the side walls, the spacers on one container being staggered from the spacers on the adjacent container to facilitate the movement of the containers toward and away from each other, and resilient means having a downwardly extending hook thereon, and a cooperating bracket for receiving the hook of another container, for connecting said containers together in tandem. 30 35

2. A shipping container having a body portion, a yoke carried by said container and a connector formed of resilient material secured to said container and vertically slidably engageable with the yoke of another container whereby adjacent 40 containers of a similar nature may be resiliently connected together.

3. A shipping container including, a body portion, a yoke connected on one end of said container, a spring bumper having an attaching 45 tongue secured on the other end of said container to provide means for connecting similar containers by said yoke and spring bumper, said spring bumper also cushioning the end movement of the shipping container and providing means for connecting the shipping container to a comple- 50 metal yoke fixed to the wall of a railroad car.

4. A shipping container including a body portion having side walls, a resilient bumper means 55 extending across one of said walls, and fixed means forming an integral part of said bumper adapted to engage an adjacent shipping container.

5. A shipping container connector for connecting adjacent containers including a resilient bumper on one container formed of resilient material, a rigid engaging projection thereon and rigid means on the adjacent container cooperat- 60 ing with said projection on said bumper for holding said containers together. 65

6. The connecting means for shipping containers including a means formed of resilient material on one container and a cooperating connecting means on a second container vertically 70 slidably engageable with the resilient connecting means of the first named container.

CHARLES C. STETSON.
